UNITED STATES PATENT OFFICE.

LEE H. ADAMSON, OF ROGERS, ARKANSAS.

DEVICE FOR PULLING AUTOMOBILES FROM MUD-HOLES.

1,241,472.

Specification of Letters Patent. Patented Sept. 25, 1917.

Application filed May 4, 1916. Serial No. 95,419.

To all whom it may concern:

Be it known that I, LEE H. ADAMSON, a citizen of the United States, residing at Rogers, in the county of Benton and State 5 of Arkansas, have invented a new and useful Device for Pulling Automobiles from Mud-Holes, of which the following is a specification.

The present invention is a device adapted 10 to be used for pulling an automobile from a mud hole or rut, and is an improvement over the device for the same purpose disclosed in my co-pending application Serial No. 73,403.

It is the object of the invention to provide 15 a novel and improved yet simple and efficacious device attachable to one of the rear wheels of an automobile, to enable the machine to extract itself from a mud hole or rut, the device including novel means for 20 anchoring it to the road or ground in advance of the rear wheel.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 25 within the scope of what is claimed without departing from the spirit of the invention.

The invention is illustrated in the accompanying drawing, wherein:

35. Figure 1 is a plan view of the device.

Fig. 2 is an enlarged plan view of the means for attachment to the automobile wheel.

Fig. 3 is an enlarged side elevation of the 40 anchor stake or pin.

Fig. 4 is a sectional detail taken on the line 4—4 of Fig. 3.

Fig. 5 is a plan view showing a modified form used with an ordinary anti-skid chain, 45 portions of which are broken away.

Fig. 6 is an enlarged side elevation of the anchoring means of the modified form.

Fig. 7 is an enlarged side elevation of a modified form of anchoring stake as driven 50 into the ground.

Fig. 8 is a fragmental elevation of another modified form of anchoring stake.

Fig. 9 is a sectional detail taken on the line 9—9 of Fig. 8.

55. Fig. 10 is a fragmental elevation showing another variation of anchoring stake.

In carrying out the invention, reference being had to Figs. 1, 2, 3 and 4, there is provided a ladder member or chain consisting of the parallel longitudinal chains or flexible elements 1 connected at suitable intervals by short cross chains or elements 2. The flexible ladder member is adapted to be wound upon the rear wheel of an automobile, and to accomplish this, one end of said member 60 is attached to the tire and felly of the wheel, through the medium of an attaching chain 3 connected to one end of one of the chains 1, and provided at its free end with a doubled member 4 terminating in hooks 5 which are 65 engageable with a link 6 attached to the respective end of the other chain 1, whereby the chain 4 and respective end chain 2 can surround the tire and felly of the wheel. The chain 3 extends around the felly, and 70 in order to prevent said chain from scratching or marring the felly, spokes, and other parts, a tubular covering 7 of rubber or other suitable material is slipped upon the chain 3, and is held in place by rivets or 75 other retaining elements 8 engaged through the covering 7 adjacent its ends and extending through certain of the links of the chain 3.

Attached to the other ends of the chains 85 1 is a yoke 9 which has attached thereto a chain or flexible element 9', and said chain 9' is connected to an anchor stake or pin 10.

The anchor stake 10 is of special construction to enhance the efficiency thereof. Thus, 90 the stake 10 embodies the flat relatively wide body or shank 11 which has one end pointed, as at 12, and said end portion of the body 11 is curved to one side from the plane of the body. The shank 11 is provided at its other end with a driving head 13, and the body 11 has a longitudinal stiffening rib or flange 14 midway between its edges and extending from the point 12 to the head 13.

100 In order to connect the chain 9' with the stake 10, a clip 15 rests against that side of the body or shank 11 of the stake opposite the rib 14, and is provided with reflexed or bent back tongues or ears 16 overlapping the other side of the shank 11, to slidably connect the clip 15 with the stake for longitudinal adjustment thereof. The clip 15 is provided with a down-turned lobe or tongue 17 provided with an aperture 18 receiving the 110 end link of the chain 9'.

The device can be readily carried within

the tool kit or other compartment of the automobile, and should the machine become stuck in a mud hole or rut, the device can readily be applied to one of the rear wheels 5 in order to enable the machine to extract itself from the rut, and if desired, one of the devices can be used for each of the rear wheels. To apply the device, the rear end of the flexible ladder member is first attached 10 to the rear wheel of the automobile in front of the rut in which the rear wheel is lodged, and the ladder member is then laid upon the road in front of the rear wheel, and the chain 9' is extended forwardly and drawn 15 comparatively taut. The stake 10 is then driven into the ground with the clip 15 resting upon the surface of the ground. Then, when the machine is started to rotate the rear wheels, the rear wheel to which the 20 ladder member is connected, will tend to wind said member thereon, thereby causing the wheel to move forwardly upon the ladder member as the ladder member is wound up, which will serve to pull the machine out of 25 the rut. The chains 1 can contact with the sides of the pneumatic tire, while the short chains 2 extend across the tread of said tire, to hold the ladder member in place or while 30 it is being wound up. After the machine is extracted from the rut, the device can be readily removed.

Particular attention is directed to the formation of the anchor stake 10, since the lower pointed end thereof is being curved 35 away from the direction in which the flexible element extends from said stake, will serve to prevent the withdrawal of the stake from the ground. Thus, referring to Fig. 3, when the pull is transmitted to the chain 40 9', there is a tendency to swing the upper end of the stake 10 toward the left, and the ground acting as a fulcrum between the ends of the stake, will swing the lower pointed end thereof toward the right, thus pulling 45 the stake 10 toward the line of pull along the chain 9', but due to the fact that the curved pointed end of the stake enters the ground at one side of the longitudinal axis of the stake, this will assist the friction of 50 the soil against the stake in resisting the tendency for the stake 10 to be withdrawn by the pull applied to the chain 9'. It is not only necessary for the pull to overcome the friction of the soil against the stake 10, but 55 it is also necessary for the pull to withdraw the soil above the lower curved or spoon-shaped end of the stake. This, ordinarily, will prevent the stake from being withdrawn during the time that the automobile is being 60 pulled from the rut. The clip 15 in resting upon the ground, applies the strain to the stake adjacent the surface of the ground, whereby there is a minimum tendency for the stake being bent, and this also

reduces to a minimum, the leverage of the 65 upper protruding portion of the stake.

In Figs. 5 and 6, the improvements are used with an ordinary anti-skid chain used upon automobile wheels, said chain embodying the longitudinal sections or chains 1' 70 connected at intervals by cross chains or elements 2'. One end of the flexible ladder member or chain is attached to the automobile wheel by means of an attaching chain 3' having terminal hooks 5' engageable with the terminal links of the chains 1', said chain 3' being adapted to pass around the felly and having a tubular covering 7' of rubber or other material held in place by means of rivets or other retaining elements 80 8' engaged through the covering 7' and certain links of the chain 3'. A pair of stakes 10' are used, one for each chain 1', and each stake comprises the shank 11' having the pointed end 12' curved to one side, head 13', 85 and stiffening rib 14', the same as the stake 10 above described. The shank 11' has an eye or staple 18' adjacent the head 13', with which a short chain section 9' is engaged, said chain section 9' having a hook 9^a to 90 engage the end of one chain 1', there being two of said chain sections 9', one for each stake 10'. Those ends of the chains 1' remote from the chain 3' can thus be anchored to the ground by means of the stakes 10'. 95 The chain sections 9' are preferably connected by a curved yoke 19' having terminals eyes 20 engaging certain links of the chain sections 9', and when the wheel passes over the yoke 19', it can be depressed to 100 accommodate the wheel when it passes between the stakes 10'.

Fig. 7 shows a modified form of anchor stake 10^a which can be used in place of either of the stakes 10 or 10', and which can also 105 be used for the attachment of a guy rope or wire. This stake 10^a has the shank 11^a, pointed end 12^a, head 13^a and rib 14^a practically the same as the stake 10. A hook 17^a integral with the head 13^a is located at that 110 side of the shank 11^a opposite the rib 14^a, and is adapted for the engagement of a chain, rope, wire, or equivalent device, and the pull can be transmitted either longitudinally of the stake in an inclined direction, 115 or horizontally along the surface of the soil away from that side of the stake toward which the pointed end thereof is curved. In order to pull the stake 10^a from the ground, it is necessary to displace and lift with the lower pointed end of the stake, the soil lying between the stake and the line 120 parallel therewith and extending from the point of the stake. This stake, as well as the others above described, is especially useful in soft ground, wherein a straight stake or pin would readily become loosened and 125 withdrawn.

The stake 10^b shown in Figs. 8 and 9 has the shank 11^b and head 13^b and rib 14^b and is provided with a web 17^b between the head 13^b and shank 11^b opposite the rib 14^b, said 5 web 17^b being provided with an aperture 18^b for the engagement of a chain, rope, wire, or the like. The stake 10^c shown in Fig. 10 has the shank 11^c, head 13^c, and rib 14^c, which rib is provided with the aperture 18^c 10 for the engagement of the chain, cable or the like.

Having thus described the invention, what is claimed as new is:

An anchor stake embodying a flat shank 15 having one end pointed and curved toward one side from the plane of said shank, said shank having a head at its other end and a

longitudinal stiffening rib between its edges and extending from said pointed end of the shank to said head, said rib being disposed 20 at that side of the shank toward which the pointed end is curved, and a clip having reflexed portions engaging said shank, the clip being disposed at that side of the shank opposite said rib, and having a downturned 25 apertured lobe for the engagement of a flexible element.

In testimony that I claim the foregoing as my own, I have hereto affixed my signature in the presence of two witnesses.

LEE H. ADAMSON.
